B. Boardman,
Blind Slat Staple.

No 19747.

Patented Mar. 30, 1858.

Fig: 1.

UNITED STATES PATENT OFFICE.

BYRON BOARDMAN, OF NORWICH, CONNECTICUT.

STAPLE FOR BLIND-SLATs.

Specification forming part of Letters Patent No. 19,747, dated March 30, 1858; Reissued March 6, 1866, No. 2,183.

To all whom it may concern:

Be it known that I, BYRON BOARDMAN, of Norwich, in New London county and State of Connecticut, have invented a new 5 and Improved Mode of Constructing the Wire Staples for Connecting Blind-Slat^s to a Rod to Guide and Govern Their Positions, and that the following is a clear and exact 10 description of the construction of the same, reference being had to the accompanying drawings, making part of this specification.

The nature of my invention consists in 15 constructing the wire staples for connecting the slats of window blinds, and screens, with indentations on the part which is to be driven into the wood, and tapering and pointing the penetrating branches of the staples in order that they may be applied or driven more readily without previous 20 boring in the wood, and that they may sustain greater force without being drawn out.

In the drawing Figure 1 *a, b, c, d*, represent an enlarged plan view of one of these 25 staples, with the side toward the observer; *e, f, g, h*, is a diagonal view exhibiting the edge of one of the staples interlocked with the former. These are shown as if completed and in positions relatively as when set. Fig. 2 represents the same staples after 30 being bent in shape, and before being serrated with indentations; the points being beveled edgewise as shown at *f* and *h*. These staples should be from three to five eighths of an inch long, with about $\frac{1}{16}$ of an inch 35 spread, and made of wire, from No. 18 to 20 wire gage. These staples after being prepared as shown at Fig. 2, are subjected to the action of dies with serrated ridges, to produce corresponding indentations in the 40 staples; and so set as to press harder, or come to a closer contact as they approach the points *a, c*, than at a distance therefrom, as at *b, d*. By this means the impressions are deeper toward the piercing points 45 than near *b, d* and the wire is spread and made to taper a little toward the point; the pressure of the dies acting at and near the extreme point, causes the beveled extremities *f, h*, Fig. 2, to assume a central position as 50 shown at *f, h*, Fig. 1; and the same action will also give a rounded edge in the other

direction as shown at *a, c*; and in this condition, the staple is completed and ready for use. The transverse indentations should slant or be beveled, in such direction as will 55 favor their driving into wood, or any other substance in which they are used, and prevent their being easily drawn out.

Some of the advantages secured over the ordinary staples now in use, in thus pointing and swaging them with transverse grooves as herein described, are, first, they may be made shorter than the ordinary staples which are not clenched, and hence will allow of a much smaller rod as they will 60 sustain from three to four times greater strain without being drawn out. Second, they will also dispense with the necessity of 65 clutching altogether, and will hold the rod equally as well, as that variety called the fishhook staple while the rod is not bruised or defaced, as when the staple is clenched. Third, they will hold as well in the slat where clutching is impracticable, as in the 70 rod, and not be liable to be drawn out by turning the slats. Finally, they may be 75 driven without previously piercing the rod or slat, as the peculiar form of the points enables them to part the grain of the wood and enter without breaking the fiber, which 80 as the staple is driven, closes into its indentations and holds it firmly embedded in the wood.

I am aware that spikes, bolts and staples for various uses have been cut with trans- 85 verse furrows, and bearded diagonally and otherwise, for the purpose of holding with greater force when driven into wood; and that stems or shanks of fishhooks have been 90 serrated with indentations for their greater security to a line; therefore I do not claim the cutting to produce a bearded or ragged surface or edge either to spikes, bolts or staples except in manner and form as herein described. Nor do I claim the production 95 of serrated indentations on the shank of fishhooks or any other article except the wire staples, such as are used for the slats of window blinds and screens. Neither do I claim the production of staples of any kind 100 when not pointed or serrated, as above described. But

What I claim as my invention and for which I solicit Letters Patent is—

Constructing wire staples, (such as are used for connecting the semi-revolving slats of window blinds and screens to a rod governing their positions) by giving them a rounded edge in the direction as shown at *a, c*, Fig. 1, and an acute or sharp edge as

viewed crosswise as at *f h*, in combination with transverse indentations across the wire 10 the whole being formed by compression between dies substantially as described.

BYRON BOARDMAN.
